HUGH CHRISTIE, OF MORRISANIA, NEW YORK.

Design No. 3,187, dated September 1, 1868.

DESIGN FOR CARPET-PATTERN.

The Schedule referred to in these Letters Patent and making part of the same.

TO ALL WHOM IT MAY CONCERN:

Be it known that I, HUGH CHRISTIE, town of Morrisania, county of Westchester, and State of New York, have invented or produced a new, original, and ornamental Design or Pattern for Carpets and other fabrics; and I do hereby declare that the accompanying pattern or drawing, marked and designated as Drab and Chintz No. 1,185, which pattern fully represents said design, is sufficient, without further aid, to enable any person skilled in the art to which it appertains to repeat it for practical use.

The colors, and the arrangement of them, may, in the use of this design, be varied to suit the views or fancy of the user or manufacturer.

What I claim as my invention, and desire to secure by Letters Patent, is—
The design or pattern for carpets and other fabrics, as shown and described.

Witnesses:

CHAS. B. KENDALL,
ROBT. P. COURTNEY.

HUGH CHRISTIE.
